(57) **CLAIM**

The ornamental design for a smart card connector, as shown and described.

DESCRIPTION

FIG. 1 is a top perspective view of a smart card connector showing my new design.

FIG. 2 is a left side view thereof.

FIG. 3 is a right side view thereof.

FIG. 4 is a front view thereof.

FIG. 5 is a rear view thereof.

FIG. 6 is a bottom view thereof; and,

FIG. 7 is a top view thereof.

The even-broken line in the drawings represents unclaimed environment and forms no part of the claimed design. The dash-dot broken line represents the boundary of the claimed design.

1 Claim, 5 Drawing Sheets

FIG. 2

FIG. 3

FIG. 4

FIG. 5

FIG. 6

FIG. 7
